(Cl. D48—27)

To all whom it may concern:

Be it known that we, David M. King and Albert Weewetzer, citizens of the United States, residing at Chicago, county of Cook, State of Illinois, and Elgin, county of Kane, and State of Illinois, respectively, have invented a new, original, and ornamental Design for a Combined Lighter and Cigarette Case, of which the following is a specification, reference being had to the accompanying drawing, forming part thereof.

We claim:

The ornamental design for a combined lighter and cigarette case, as shown.

DAVID M. KING,
ALBERT WEWETZER.
